REFRIGERATING APPARATUS

Peter B. Loomis, Birmingham, Mich., assignor to
Borg-Warner Corporation, a corporation of
Illinois

Application December 24, 1936, Serial No. 117,432

3 Claims. (Cl. 62—6)

This invention relates to refrigerating apparatus in general and has particular reference to improvements in refrigerating systems, to improvements in the elements or apparatus used therein, and to a system or method of and apparatus for producing refrigeration either at a single temperature or at a plurality of selected different temperatures at the same time.

The refrigerating system selected for purposes of illustration includes an evaporator having two sections, one being disposed within the other and separated therefrom, and the two as a unit contemplating the disposal thereof within a heat insulated compartment. The outside evaporator section, namely, the box cooling coil, is adapted for producing refrigeration, during normal operation, at a temperature similar to that produced by the inner, or freezing, evaporator section; this temperature is such that the latter section keeps ice cubes in their frozen condition. Of the two evaporator sections the outside section is the one having the more constant refrigerating effect, operating within the limits of about 23° F. to 31° F., whereas the inner section is adapted for selective temperature variations, its operation being between, say, 5° F. and 27° F. The system, because of the food compartment of the cabinet being shielded from the freezing section, during two-temperature operation of the system, is adapted to maintain a constantly high relative humidity within the heat insulated compartment whereby the quality of the foods stored therein will not be jeopardized by the low temperature of the inner section. It might be said at this time that the accumulator or header for the freezing section of the evaporator contemplates the provision therein of a conventional means for returning the lubricant therefrom, by entrainment, to the compressor through the system suction line, although this means is not disclosed.

In addition to the two-section evaporator the system includes a valve which is adjustable for creating a pressure differential between the two evaporator sections and which maintains this differential until the operator no longer desires two-temperature operation. The valve is provided with means for manually creating this pressure differential between the two evaporator sections, thus offering a system which is adapted for, say, keeping ice cream in its frozen condition, or for single-temperature operation in general.

The invention contemplates the use therein of any type of valve which provides little or no re-

striction in the passageway between the evaporator sections during single-temperature operation of the system but which is manually operable to partially restrict said passageway so as to provide a refrigerating system the evaporator sections of which are operable at different pressures, and thus, different temperatures, when such is desirable.

The system, in addition to the two-section evaporator and the shelf temperature adjustment valve, includes any efficient and ordinary condensing unit which itself includes a compressor of any desirable type. Although undisclosed, the suction pressure inlet port of the compressor is provided with a check valve which is adapted to maintain a difference in pressure between the system suction line and compressor suction chamber while the compressor is at rest. Associated with the condensing unit and the two-section evaporator, and disposed in the high pressure feed line therebetween, and dividing the system into a high and low pressure side, is a high-side float valve of the type known to the industry today.

The principal object of the present invention is to utilize in an ordinary heat insulated cabinet an evaporator or heat absorbing means having two sections, one of said sections being maintained between relatively constant temperature limits during normal operation of the system, and the other of said sections being maintained within approximately the same temperature limits during said normal operation of the system, but which may be independently subjected to a substantially lower pressure according to the wants of the operator, thereby producing therein a correspondingly lower temperature than in said former section.

Another object of this invention is to provide a system of refrigeration which normally operates at a unitary temperature, but which may be turned into a two-temperature refrigerating system whenever desired by the operator.

Another object of this invention is to provide a system of refrigeration adapted for optional operation either at a single temperature or at two simultaneously different temperatures and which is comprised of fewer working parts than systems at present used, thereby providing a system which is not only simple and compact but also inexpensive in initial and operating costs.

Another object of this invention is to provide in a system of refrigeration an adjusting means adapted for association with the cooling and freezing coils of the evaporator for operating the system as a whole at a unitary temperature dur-

ing normal operation thereof, or for operating the system as a two-temperature system when so desired.

Another object of this invention is to provide in conjunction with a system of refrigeration employing a pair of evaporators in series a temperature adjusting means between the two evaporator coils which is provided with a constantly open by-pass regardless of the condition of adjustment thereof.

Another object of this invention is to provide a method or system of refrigeration, and the apparatus for performing same, which produces a plurality of different temperatures simultaneously with the production of a plurality of different relative humidities, each temperature and its corresponding relative humidity representing the most favorable operating conditions for the particular part of the apparatus in which same are produced, and each relative humidity being substantially independent of the other.

Another object of this invention is to provide in a single refrigerating system a plurality of evaporators or cooling coils separated from each other and having means therebetween for selectively producing different suction pressures so as to obtain different temperature conditions in each of said coils of the evaporator.

Other objects and advantages of the invention will be apparent from a consideration of the following specification taken in conjunction with the accompanying drawing of which there is one sheet and in which:

Fig. 1 is a diagrammatic view of a refrigerating system embodying the invention herein disclosed;

Fig. 2 is a part sectional view taken along the lines 2—2 of Fig. 1 and showing in detail a modification of the means utilized in Fig. 1 for producing the optional single- or two-temperature refrigeration; and

Fig. 3 is a view taken along the lines 3—3 of Fig. 2 and showing more in detail the head of and stop for the valve disclosed in Fig. 2.

In Fig. 1 there is illustrated a condensing unit, generally indicated at 10, adapted for supplying liquid refrigerant to the evaporators and removing vaporous refrigerant therefrom. Unit 10 comprises a compressor, generally indicated at 11, possessing an inlet port 12 (which includes an undisclosed check valve) and a discharge port 14 to the latter of which is connected a compressed refrigerant conduit 16 which develops itself into a condenser, generally indicated at 18. Disposed effectively with relation to condenser 18 for dispensing with much of the heat surrounding same is a blower unit 20 which is operated by the same means 21 as that which, by a belt (not shown), drives the compressor 11. The condensing unit 10 is suitably supported by means of a support 24.

Condenser 18 is operatively connected by a high side fluid feed line 26 which includes therein a high side float valve, generally indicated at 28. Valve 28 divides the system into a low and a high pressure side and is an ordinary high side float valve which is well known to the industry and comprises, in general, a float 30 which is adapted to operate according to the quantity of fluid passing through the valve. As soon as enough fluid is built up behind and within valve 28 to operate the float 30, the valve opens and the high pressure fluid refrigerant is allowed to pass through the valve and into another section 32 of said line 26. The exposed portion of feed line 32 is heavily insulated to prevent refrigeration of the surrounding air, and loss of efficiency thereby,

and terminates in the box coil section of the evaporator, generally indicated at 34.

The box coil 34 comprises a series of horizontally and vertically disposed tube sections joined together along their edges to form a continuous shield which empty into a series of horizontally disposed headers 36. Coil 34 and headers 36 are adapted for continuous circulation of fluid and partially vaporous refrigerant therethrough.

10 Disposed within and shielded from the food compartment by the box coil 34 is the shelf coil, generally indicated at 38, of the evaporator unit. One end of coil 38 is connected to a portion of the upper part of coil 34 for fluid refrigerant 15 communication therebetween. The other end of shelf coil 38 is connected to an accumulator 40. Shelf coil 38 comprises a plurality of horizontally and vertically disposed tube sections which are properly placed for heat exchange relationship 20 between the tube sections and a plurality of shelves 42 on which ice trays may be placed.

To a portion of accumulator 40 which lies above the liquid level therein is connected one end of the system suction line 44 the other end of 25 which is connected to the suction pressure inlet port 12 of compressor 11 through a check valve (not shown) in port 12.

Fig. 2 illustrates, in detail, the shelf temperature adjustment valve, generally indicated at 47, 30 which appears in the two-temperature refrigerating system shown in Fig. 1. Valve 47 comprises a body member 50 formed internally thereof to provide a bore 52 in which a piston 54 is adapted to reciprocate relative thereto. On one 35 side of piston 54 of valve 47, and adjacent thereto, is a coil spring 56 which is telescoped by a collapsible bellows 58, said bellows being bonded or otherwise secured to a flange provided therefor on piston 54 and to the forward end of body 40 member 50. On the other side of piston 54 of valve 47, and adjacent thereto, is another coil spring 60 which is oppositely and symmetrically disposed with relation to the other spring 56, and is seated on a shoulder provided therefor on piston 54. The end of spring 60 which is opposite 45 to the piston 54 is adapted to rest against a shoulder provided therefor in body member 50 and extending into bore 52.

Integral with and projecting from one side of 50 piston 54 is a valve stem 62 adapted for minute reciprocation relative to an opening 64 provided therefor in body member 50. The end of valve stem 62 opposite the piston 54 is provided with an enlarged head 66, the under-portion of which 55 is beveled and adapted to define the inner circumference of an annular ring-shaped area with one corner of the aforementioned shoulder of body member 50 defining the outer circumference of said area when the valve is in its seated 60 position. This ring-shaped area is one of the two means for providing a communication in the otherwise-restricted passageway between coils 34 and 38 when the valve is closed. The enlarged head 66 is provided with a still larger annular 65 flanged head 68 which is disposed in a bore 70 provided therefor in the body member 50.

The under-side of flanged portion 68 of valve head 66 is adapted to be seated on a series of radially projecting lugs 72 which are integral with 70 the body member 50 and extend radially into bore 70 to such an extent as to provide a suitable seat for the flanged portion 68. It will be seen that the diameter of portion 68 is less than the diameter of bore 70, and that the ring-shaped 75 area defined between the wall of bore 70 and the

periphery of flange 68, broken only by the space occupied by lugs 72, provides the second aforementioned communication in the otherwise restricted passageway between coils 34 and 38 when the valve is in its seated position.

The reason for providing a valve which communicates the refrigerant on either side thereof with the suction side of the compressor, even when said valve is closed, is, of course, to enable the box coil to be continuously operated at a temperature sufficiently low enough so that foods can be stored in the heat insulated compartment and kept without being frozen and, as well, without deteriorating. This temperature ranges between the limits, as has already been said, of about 23° F. and 31° F., the box temperature being kept in the neighborhood of, say, 35° F. and, no matter at what temperature the shelf coil is being operated, these box coil temperature limits will be maintained, since the valve provided herein offers the same amount of communication therethrough regardless of how securely it is seated. In other words, this system provides a relatively constant box coil temperature during normal or abnormal shelf coil operating conditions.

Provided in the body member 50 and adapted for associating box coil 34 with bore 10 and shelf coil 38 with bore 52, respectively, is a pair of openings 74 and 76. Coils 34 and 38 may be joined to body member 50 of valve 47 in any appropriate manner such as by co-relation between threaded portions of the coils and threaded portions provided therefor in body member 50.

In order to close the valve mechanism from the atmosphere there is provided a heavy cap member 80 which is formed internally thereof to provide a threaded bore 82 in which a valve adjustment handle 84 (advisedly insulated) is adapted to be adjustably disposed. Opposite the handle portion of member 84 there is provided a portion 86 which is adapted to be telescoped by one end of spring 56, said end of spring 56 being adapted to rest against a shoulder portion 88 of handle 84. Members 80 and 50 are joined together, with the forwardly flanged portion of bellows 58 interposed therebetween, by means of a series of cap screws 90 which extend through openings provided therefor in member 80 and into threaded portions provided therefor in member 50. A hole 92 is provided in member 84 and extends axially therethrough to communicate the atmosphere with the chamber enclosed by the bellows 58.

The valve 47 is the means by which a refrigerating system can be operated as either a single- or two-temperature system according to the wants of the operator. And, it must be remembered that the valve, when closed, should have a constantly open by-pass, and, when open, should provide as little restriction as possible to the fluid passing therethrough.

A dial 94, or other form of indicating means, is secured to the face of cap member 80 adjacent the handle 84 and is provided with spaced numerals thereon showing the proper positions of handle 84 for the corresponding shelf temperatures.

In order to maintain the box cooling coil between the aforementioned temperature limits a thermostatic bulb 96 is secured to the coil and has thermally associated therewith a thermally operated switch 97 which is connected in series with the electric current used to operate the compressor motivating means and conducted by conduits 98.

The system described in the above paragraphs operates in the following manners:

The vaporous refrigerant which is compressed by compressor 11 is discharged through the outlet part 14, the conduit 16, and into and through the condenser 18 wherein the ensuing heat exchange causes the vapor to condense. From condenser 18 the liquid refrigerant passes through feed line 26 and into float valve 28. When enough fluid comes in contact with valve 28 to operate the float 30, the float opens and fluid is allowed to pass therefrom into and through the line 32. The fluid then passes into coil 34, into and through the open valve 47 and coil 38, and fills same up to a varying level in accumulator 40. In the process of passing through the coils 34 and 38 the refrigerant is evaporated, such action causing the temperature of the refrigerant in both coils to drop. The gas which is formed by the evaporation, together with minute quantities of entrained lubricant, pass from the accumulator 40 into and through the system suction line 44 and thence into and through the check valve (not shown) and the suction port 12 of the compressor. The cycle is then ready to be repeated.

During normal operation of the system, the valve 47 is in its open position and both the box coil and the shelf coil are maintained at practically the same pressure. There is a slight difference in temperature, however, between the two coils, and this difference is caused by the heat of the fins on the box coil, such heat not affecting the shelf coil because of the shielding effect between it and the box coil. The most economical operating condition is when the valve is in this open position and the temperatures in the two coils are low enough to freeze water and to keep the ice cubes in their frozen condition, but not low enough to keep ice cream.

If it is desired to keep ice cream after it has been frozen, or to otherwise have the system operate as a two-temperature apparatus, it is necessary for the operator to adjust the valve handle 84 of valve 47 so that the pressure on spring 56 will be relieved. The valve will then have its head permanently seated, and the system will operate with a normal operating pressure in the box coil and a much lower pressure in the shelf coil.

In order to return to single-temperature operation, the operator must turn handle 84 back to its original position so that piston 54 is forced to the right against the opposition of spring 56 and thereby causing the unseating of valve head 68.

It is to be understood that the invention is not limited to the specific features of the figures and system disclosed, but is to be considered broadly as is represented by the scope of the appended claims.

I claim:

1. A cooling unit comprising an inner evaporator section and an outer evaporator section enclosing the first mentioned section; a conduit for supplying liquid refrigerant to said outer section and a second conduit for removing vaporized refrigerant from the inner section; means for conducting refrigerant from one of said sections to the other; a control device interposed in said means and comprising a valve member shiftable to one position to permit unrestricted flow of refrigerant from the outer to the inner section or to a second position in which it cuts down such flow; and a manually operable element accessible

from the exterior of said outer section and connected to said valve member for shifting the same, said device being constructed to permit a flow of at least a predetermined amount of refrigerant from said outer to said inner section at all times when said unit is in operation.

2. In a refrigerating unit including an ice freezing compartment and a food cooling compartment, a two-section evaporator comprising a first section located in said freezing compartment 10 and a second section located in said food cooling compartment, means connecting said first section with said second section, said means being particularly characterized by the provision of manually adjustable pressure governing means 15 for controlling the pressure in said evaporator sections, whereby said system is convertible at will from or to a single temperature system into or from a two temperature system and means for supplying said first evaporator with liquid refrigerant and for removing vaporous refrigerant from said second evaporator section.

3. In a refrigerating unit including an ice freezing compartment and a food cooling compartment, a two-section evaporator comprising 20 a first section located in said freezing compartment and a second section located in said food

cooling compartment, means connecting said first section with said second section, said means being particularly characterized by the provision of manually adjustable pressure governing means for controlling the pressure in said evaporator sections, whereby said system is convertible at will from or to a single temperature system into or from a two temperature system and means for supplying said first evaporator with liquid refrigerant and for removing vaporous refrigerant from said second evaporator section, said connecting means between said evaporator sections being further particularly characterized by the fact that the same comprises a body member formed with an internal bore, said bore being provided with a valve seat, said valve seat having interrupted portions, a reciprocable valve member having a first position in engagement with said seat providing for a limited passage of fluid thereby between said valve and said interrupted seat, and a second position providing for substantially uninterrupted flow past said valve, and manual means for selectively moving said valve to either said first position or said second position.

PETER B. LOOMIS.
